CLAIM

The ornamental design for a pistol, as shown and described.

DESCRIPTION

1. Pistol

1.1 : Perspective

1.2 : Perspective

1.3 : Left

1.4 : Right

1.5 : Front

1.6 : Back

1.7 : Top

1.8 : Bottom

The trademark FN, having an oval shape and which is on both the slide and on the handle of the pistol, forms no part of the present design; the knurling that appears on the sides of the handle forms no part of the present design.
